UNITED STATES PATENT OFFICE

153,603

DESIGN FOR A RAILWAY DINING CAR BODY

Ralph W. Haman, Flossmoor, Ill., assignor to
Pullman-Standard Car Manufacturing Company,
Chicago, Ill., a corporation of Delaware

Application September 20, 1947, Serial No. 141,499

Term of patent 14 years

(Cl. D66—1)

To all whom it may concern:

Be it known that I, Ralph W. Haman, a citizen of the United States of America, and resident of Flossmoor, county of Cook, and State of Illinois, have invented a new, original, and ornamental Design for a Railway Dining Car Body, of which the following is a specification, reference being had to the accompanying drawings, forming part thereof.

In the drawings—

Fig. 1 is a general perspective view of a railway car body of the type in which my new design of dining room is incorporated and having portions broken away to reveal the arrangement of the dining room within the body, and indicating the supporting trucks in dotted lines for purely illustrative purposes;

Fig. 2 is a partial plan view of the railway car body interior showing my new design of dining room adjacent to one end of the car, with the kitchen area adjoining the other end of the dining room;

Fig. 3 is a general perspective view of my new design of dining room in the railway car body looking in the direction of the end area of the car; and

Fig. 4 also is a general perspective view of my new design of dining room, but to larger scale and looking in the opposite direction, toward the entrance to the kitchen and passageway.

What is claimed is:

The ornamental design for a railway dining car body, substantially as shown and described.

RALPH W. HAMAN.
